HAND SPRAYER

Charles E. Hays, Kansas City, Mo., assignor to H. D. Hudson Manufacturing Company, Chicago, Ill., a corporation of Minnesota

Filed Jan. 19, 1959, Ser. No. 787,625

3 Claims. (Cl. 239—331)

This invention relates to new and useful improvements in sprayers, and has particular reference to sprayers of the hand-operated, portable type. Still more specifically, the invention relates to a sprayer of the reciprocating type, and therefore includes a relatively reciprocable cylinder and plunger pump operable to draw the liquid to be sprayed from a tank and to deliver it to a nozzle from which it is discharged.

In previous sprayers of this type within my knowledge the pump device delivers the liquid directly from the tank to the nozzle. Since the liquid itself is of course substantially incompressible, this structure required continuous manual operation of the pump as long as it was desired to continue the spraying action. When spraying in positions of difficult access, this requirement often resulted in extremely awkward and inconvenient manipulation. Therefore it is a principal object of the present invention to overcome this difficulty by providing means whereby the spraying action may be maintained for substantial periods of time after the pumping action has been halted. Generally, this object is accomplished by providing a reservoir intermediate the pump and the nozzle, said reservoir being adapted to receive liquid from said pump and in which said liquid is maintained under pressure by a spring-loaded piston, the reservoir being enlarged by movement of said piston against its loading spring. Since the nozzle itself constitutes an extreme flow restriction, rapid operation of the pump will fill the reservoir and compress the loading spring. Thereafter, spraying action will be maintained until the loading spring has fully recovered.

Another object is the provision in a sprayer of the class described, of a regulating and shut-off valve between the reservoir and the nozzle, whereby the rate of discharge from the reservoir may be controlled, and whereby the spraying action may, if desired, be delayed until the reservoir is fully charged and the nozzle is properly positioned relative to the object to be sprayed.

Still another object is the provision of a sprayer as described wherein the nozzle is carried by an angled tube attached rigidly to the plunger of the pump, said plunger being axially rotatable relative to the cylinder of the pump, and wherein said reservoir constitutes a cylinder affixed to and extending transversely from said nozzle tube, whereby said pump and reservoir cylinders are adapted to serve as handles both for reciprocal operation of the pump and for rotation of said nozzle tube to direct the nozzle as desired.

Other objects are simplicity and economy of construction, efficiency and dependability of operation, and adaptability for use in a wide variety of applications.

With these objects in view, as well as other objects which will appear in the course of the specification, reference will be had to the drawing, wherein:

Fig. 1 is a side elevational view of a sprayer embodying the present invention.

Fig. 2 is an enlarged fragmentary sectional view of the sprayer, showing the pump section and related parts thereof.

2

Fig. 3 is an enlarged, fragmentary sectional view of the sprayer, showing the reservoir section thereof.

Fig. 4 is an enlarged sectional view of the nozzle and the valve incorporated therein, with parts left in elevation, and

5 Figs. 5 and 6 are sectional views taken respectively on lines V—V and VI—VI of Fig. 4.

Like reference numerals apply to similar parts throughout the several views, and the numeral 2 applies to a 10 tubular pump cylinder. The rearward end of said cylinder is closed by a fitting 4 welded or otherwise fixed therein. As best shown in Fig. 2, fitting is tubular, and is affixed to the screw cap 6 of a bottle or tank 8 adapted to carry the liquid to be sprayed by means of a tubular 15 flanged nipple 10 extending through said cap and threaded into the lower portion of fitting 4. Thus the interior of tank 8 is interconnected with the interior of cylinder 2. A tube or hose 12 is attached to nipple 10, and depends into the bottom portion of tank 8. Cap 6 is vented to the 20 atmosphere at 14. Cylinder 2 is further secured to cap 6 by means of a U-bolt 16 straddling said cylinder and secured in cap 6 as by nut 18. A valve ball 20 is mounted loosely in an interior bore 22 of fitting 4, and is retained therein by a pin 24 carried by said fitting and extending 25 transversely across said bore. Said ball cooperates with a valve seat 26 formed by bore 22 to permit flow of liquid from tank 8 to cylinder 2, but to prevent flow in a reverse direction.

A tubular pump plunger 28 is disposed concentrically 30 within cylinder 2 and extends outwardly from the forward end thereof. Said plunger is of smaller diameter than cylinder 2, whereby to form an annular chamber 30 therebetween. At its rearward end, within cylinder 2, plunger 28 is provided with a tubular piston 32 sealed in cylinder 35 2 by a compressible O-ring 34, and having a portion 36 of reduced diameter inserted slidably into plunger 28. A valve ball 38 is carried loosely in the central bore 40 of the piston, and is retained therein by a pin 42 extending transversely across said bore. Said pin passes through 40 both the walls of the reduced piston portion 36 and the walls of plunger 28, so as to serve also to affix said piston to said plunger. Valve ball 38 cooperates with a valve seat 44 formed in bore 40 to permit flow of liquid from cylinder 2 into plunger 28, but to prevent flow in a reverse 45 direction. Just forwardly from piston 32, one or more holes 46 are formed in plunger 28 to communicate with the annular chamber 30 between said plunger and cylinder 2. Just forwardly from holes 46, a second pin 48 is inserted transversely through the plunger, the ends 50 thereof projecting into chamber 30 for a purpose which will presently appear.

At its forward end, cylinder 2 has a cylindrical fitting 50 welded or otherwise affixed thereto, and an annular bushing 52 is inserted slidably between said fitting and plunger 28. Said bushing is sealed against fitting 50 by a compressible O-ring 54, and is sealed against plunger 28 by a compressible O-ring 56. The bushing is retained in place, and the O-rings are compressed, by a clamping ring 58 threaded on fitting 50. It will be seen that as plunger 28 is moved forwardly, ball 38 will be seated and ball 20 will be unseated, and liquid from tank 8 will be drawn upwardly through hose 12 and fittings 10 and 4 into cylinder 2. When the plunger is moved rearwardly, ball 38 will be unseated and ball 20 will be seated, and liquid will be forced from cylinder 2 through piston 32 into plunger 28, and through holes 46 into chamber 30. On the next forward stroke of the plunger, liquid will be forced from chamber 30 through holes 46 into plunger 28 and forwardly therethrough. Hence, so long as the 60 system is full of liquid, the pump is double-acting, and will deliver liquid forwardly through plunger 28 on every forward and every rearward stroke of the plunger. The 65 70

end portions of pin 48 engage the inner end of bushing 52 to prevent the plunger from being entirely withdrawn from the cylinder, and to prevent exposure of the holes 46 forwardly of the cylinder.

A liquid reservoir 60 is attached to the forwardly extended end of plunger 28. Said reservoir comprises a tubular cylinder closed at its upper end by a domed cap 62 welded or otherwise fixed thereto and having a depending cylindrical skirt 64 inserted into said cylinder. The forward end of plunger 28 is inserted through cylinder 60 and cap skirt 64 and is affixed therein to communicate with the interior of said cylinder. A nozzle tube 66 is similarly inserted and secured, and is disposed in alignment with plunger 28. Obviously the plunger and nozzle tube may be designated as a single tubular member with the reservoir 60 interposed intermediate the ends thereof. A piston 68 is disposed slidably in cylinder 60, being sealed therein by a pair of O-rings 70, and is urged upwardly to abut the lower end of cap skirt 64 by a compression spring 72. Said spring is disposed axially within cylinder 60, bearing at its upper end against piston 68, and at its lower end against a pin 74 extending transversely across said cylinder, said pin having hooked end portions 76 engaged in holes 78 formed in the cylinder wall. It will be apparent that if, by the pumping action previously discussed, liquid is delivered to reservoir 60 through plunger 28 more rapidly than it is carried away from said reservoir by nozzle tube 66, then the pressure in said reservoir will increase, and piston 68 will be forced downwardly against the pressure of spring 72, thereby increasing the volume of the reservoir to accommodate the excess liquid. After the pumping action is halted, spring 72 will function to urge liquid forwardly through the nozzle tube, until piston 68 again abuts cap skirt 64.

The forward end portion 80 of nozzle tube 66 is angled relative to the major portion of said tube, and to the extreme end of said angled portion is attached a spray head and valve assembly indicated generally by the numeral 82. As best shown in Fig. 4, said assembly includes a generally cylindrical and tubular body member 84 which is inserted in and welded or otherwise fixed in the end of tube 66. The bore 86 of said body member is of enlarged diameter at the outer end portion 88 thereof, the juncture between bores 86 and 88 being bevelled to form a tapered valve seat 90. Carried slidably in bore 88 is a valve stem 92 having a tapered point 94 which cooperates with valve seat 90. The valve stem is provided at its outer end with an enlarged circular head 96 having a transverse slot 98 formed in the outer end surface thereof. The portion 100 of body member 84 is of the same diameter as valve stem head 96, and a fine mesh screen cylinder 102 is fitted snugly around body portion 100 and head 96, although the valve stem must of course still be free to move axially. Body portion 100 also has longitudinal slots 104 formed therein, and peripheral grooves 106 formed in the external surface thereof. Said slots and grooves form passages whereby liquid entering body section 100 through valve members 90-94 is distributed evenly over the inner surface of screen cylinder 102 and passes outwardly therethrough.

A generally tubular sleeve 108 is fitted coaxially over body member 84, said sleeve being internally threaded at 110 to engage threads 112 formed externally on the body member. Said sleeve has a greater internal diameter than the external diameter of screen cylinder 102, whereby to form an annular chamber 112' for receiving the liquid passing outwardly through strainer screen 102. The inner end portion of sleeve 108 is sealed against body member 84, whereby to prevent leakage of liquid therebetween, by a compressible O-ring 114 carried in a peripheral groove 116 of said body member. Sleeve 108 is provided at its outer end with an outlet 118, and with an inwardly facing internal shoulder 120 adjacent said outlet. Said shoulder abuts the outer end of valve stem head 96. Thus when sleeve 108 is screwed inwardly on body mem-

ber 84, shoulder 120 urges valve stem 92 inwardly to press the tapered point 94 thereof firmly against valve seat 90, and no liquid can flow. When the sleeve is screwed outwardly, it frees the valve stem, which is then forced outwardly by liquid pressure to open the valve. The liquid then flows outwardly through strainer screen 102 into chamber 112', and through slot 98 of head 96 to the sleeve outlet 118. Affixed to the forward end of the sleeve, and adapted to receive liquid from outlet 118 thereof, is a spray head 122 which contains suitable means for atomizing the liquid and ejecting it in a spray as may be desired. Spray heads of this general type are well known, and since the specific details thereof are not pertinent to this invention, they are not here shown or described.

Thus it will be apparent that a sprayer having several advantages has been produced. The pump is double-acting, and will deliver liquid on every stroke. The liquid may be stored in reservoir 60 under the pressure of spring 72, and the spraying action will therefore continue long after the reciprocal pumping action has been stopped. Since the liquid itself is stored under direct mechanical pressure, the reservoir may be much smaller, and requires fewer strokes of the pump to fill it, than is required to provide a comparable operating time in previous sprayers wherein the liquid is loaded by air pumped into a closed vessel containing the liquid. Since the nozzle tube is rotatable about its axis, and is angled to that such rotation will control the direction of spraying, and since reservoir 60 extends transversely from the nozzle tube, said reservoir serves as a handle whereby the spray direction may be controlled conveniently and easily, and also as a handle for reciprocating plunger 28 in cylinder 2. The valve 90-94 permits the regulation of liquid flow to the nozzle, and also as a complete shut-off. The latter function is useful in permitting full charging of the reservoir before any spraying occurs, as may be required when spraying must be done while holding the sprayer in awkward positions in which it may be difficult or impossible to reciprocate the plunger. Also, the shut-off feature is valuable in that it permits shutting the sprayer off with the reservoir still partially charged, thereby in many cases avoiding wastage of the spray liquid.

While I have illustrated and described a specific embodiment of my invention, it will be readily apparent that many minor changes of structure and operation could be made without departing from the spirit of the invention as defined by the scope of the appended claims.

What I claim as new and desire to protect by Letters Patent is:

1. A manually-operated hydraulic spraying device consisting of a container for spray solution, a fitting on said container having a non-return valve permitting flow from said container but preventing flow in a reverse direction, a tubular pump including a cylinder connected at one end to the fitting for receiving spray solution from said container with said cylinder providing the pressure chamber of the pump, a tubular reciprocating plunger arranged within said cylinder and spaced concentrically therefrom to provide an annular storage chamber therebetween, a piston in and having sealing engagement with said cylinder and affixed to the inner end of said tubular plunger with said piston having a central flow passage and a non-return valve, the tubular wall of said plunger having one or more openings adjacent said piston and communicating with said annular storage chamber, a fitting on the other end of said cylinder having sliding and sealing contact with the encompassed tubular wall of said plunger and providing a sealing closure for the outer end of the annular storage chamber, a spring-actuated pressure accumulator affixed to the outer end and communicating with the interior of said tubular plunger, said accumulator having a tubular housing closed at its upper end and open at its lower end, an abutment at its lower end, the open outer end of the tubular plunger

communicating with the interior of said housing, a piston slidably mounted in said housing below the communicating tubular plunger, a compression spring having one end bearing against said piston and the other end bearing against said abutment at the lower open end of the housing, said container and said housing depending laterally from the longitudinal axis of the tubular pump to provide spaced handles to be grasped by the operator for reciprocating said tubular plunger and directing the spray solution during spraying operation, a nozzle tube having one end opening into the accumulator housing, and an adjustable spray head on the other end of the nozzle tube for controlling discharge of the spray solution upon reciprocation of the pump.

2. In a manually-operated hydraulic spraying device, a container for spray solution, a fitting on said container and a non-return valve permitting flow from said container but preventing flow in a reverse direction, a tubular pump including a cylinder connected at one end to the fitting for receiving spray solution from said container with said cylinder providing the pressure chamber of the pump, a tubular reciprocating plunger arranged within said cylinder and spaced concentrically therefrom to provide an annular storage chamber therebetween, a piston in and having sealing engagement with said cylinder and affixed to the inner end of said tubular plunger with said piston having a central flow passage and a non-return valve, the tubular wall of said plunger having one or more openings adjacent said piston and communicating with said annular storage chamber, a fitting on the other end of said cylinder having sliding and sealing contact with the encompassed tubular wall of said plunger and providing a closure for one end of said annular storage chamber, a spring-actuated pressure accumulator affixed to the other end of and communicating with the interior of said tubular plunger, said accumulator including an open-ended tubular housing having an abutment at its lower open end, a cap providing a closure affixed to the upper end of said housing and into which extends the open outer end of said tubular plunger, a piston slidably mounted in said housing, a compression spring having one end bearing against said piston and the other end bearing against said abutment at the lower open end of the housing, said container and said housing depending laterally from the longitudinal axis of the tubular pump to provide handles for reciprocating said tubular plunger and directing the spray solution during spraying operation, a nozzle tube having one end opening into the cap of the accumulator housing opposite the tubular plunger, and an adjustable spray head and contained valve assembly connected to the discharge end of said nozzle tube.

3. In a manually-operated hydraulic spraying device, a container for spray solution, a fitting on said container having a non-return valve permitting flow from said container but preventing flow in a reverse direction, a tubular pump including a cylinder connected at one end to the fitting for receiving spray solution from said container with said cylinder providing the pressure chamber of

the pump, a tubular reciprocating plunger arranged within said cylinder and spaced concentrically therefrom to provide an annular storage chamber therebetween, a piston in said cylinder and affixed to the inner end of said plunger with said piston having sealing contact with the interior of the cylinder and a central flow passage and a non-return valve therein, the tubular wall of said plunger having one or more openings adjacent said piston and communicating with said annular storage chamber, a fitting on the other end of said cylinder having sliding and sealing contact with the encompassed tubular wall of said plunger and providing a closure for the forward end of said annular storage chamber, means secured to the tubular plunger and adapted to contact said last mentioned fitting to limit reciprocatory movement of said tubular plunger in said cylinder, a spring-actuated pressure accumulator affixed to the outer end of and communicating with the interior of said plunger, said accumulator providing a reservoir for the spray solution under pressure and also a depending handle for reciprocating said plunger and for directing the spray solution during spraying operation, a nozzle tube having one end opening into said accumulator and an adjustable spray head and valve assembly on the discharge end of said nozzle tube, said spray head and valve assembly including a body member, a tubular sleeve adjustably mounted on said body member, said body member being connected to said nozzle tube and having a bore of smaller diameter than the opening of said nozzle tube and a communicating larger bore, a tapered valve seat at the outer end of said reduced bore opening into said larger bore, a valve member having a valve stem slidable in said larger bore and provided with a tapered part adapted to be conformably received in said tapered valve seat for closing flow through said communicating bores, an enlarged head on said valve member, said body member being longitudinally and peripherally slotted along the larger bore, a screen encompassing said body member along its slotted portion and spaced from the interior of the encompassing sleeve to provide an annular chamber for the spray solution passing outwardly through said screen when the valve member is open, and a shoulder on said encompassing sleeve abutting said enlarged valve head to close the valve member upon adjustment of said sleeve in one direction and when said sleeve is adjusted in the other direction flow through said nozzle tube of the spray solution under pressure opens said valve member.
